UNITED STATES PATENT OFFICE.

JAMES L. RAY, OF SWARTHMORE, PENNSYLVANIA, ASSIGNOR TO WESTINGHOUSE ELECTRIC & MANUFACTURING COMPANY, A CORPORATION OF PENNSYLVANIA.

TURBINE-BLADE LASHING.

Application filed September 12, 1925. Serial No. 56,039.

My invention relates to elastic fluid turbines more particularly to the blading thereof and has for its object the provision of an efficient lashing for turbine blades which shall provide the maximum of stiffness to the blading structure with a minimum of resistance to motive fluid flowing through the blades.

Apparatus embodying features of my invention is illustrated in the accompanying drawings, forming a part of this specification, in which Fig. 1 is a fragmentary sectional view of a turbine blade carrying element having a segment of blades mounted thereon provided with my improved lashing; Fig. 2 is a fragmentary sectional view of two blades having a modified form of my invention applied thereto; Fig. 3 is a sectional view, in plan, of the structure shown in Fig. 2; Fig. 4 is a sectional view, in plan, of two blades illustrating a further modification of my invention; and Fig. 5 illustrates a method of lashing a segment of blades in accordance with Fig. 4.

As is well understood in the turbine art, the function of blade lashing is to minimize as far as possible vibration of the blading. This is accomplished by bracing the blades by means of one or more rows of lashing so as to raise the natural period of vibration of the blades above, or out of harmony with that of the disturbing factors in turbine operation which induce vibration. To give stiffness to the blading structure it is necessary therefore that the lashing present a maximum of resistance to bending in the plane of vibration. While it would be entirely possible to provide a single lashing member sufficiently heavy to perform this function, its practical application is under certain circumstances impracticable. If a round lashing wire of sufficient diameter is employed, the resistance to motive fluid flow through the blades is increased and the efficiency of the turbine is impaired. On the other hand, if a lashing member of relatively small section in the direction of motive fluid flow and flattened across the face of the blade is employed, its attachment to the blades is expensive and tedious and its moment of resistance or stiffening effect is low in proportion to its bulk. Confronted with these difficulties the turbine designer has usually provided a blade lashing which is a compromise as to strength and impedance

to motive fluid flow and has added strength to the structure by multiplying the rows of lashing applied.

In accordance with my invention, I have overcome the before mentioned difficulties by providing lashing means attached at two points to each of the blades in a segment of blades and join the members together intermediate the blades, preferably by fusion of metal, such as welding, soldering or brazing. The lashing may comprise two lashing wires drawn together and joined intermediate the blades of a row, or may be in the form of individual rings or links applied to each blade in the process of manufacture and joined together intermediate the blades upon assembly. With either form, the minimum of resistance to motive fluid flow is effected, together with a maximum of resistance to flexure and hence to vibration.

Referring now to the drawings for a better understanding of my invention, I show in Fig. 1 at 10 a fragment of a blade carrying element, for example, a turbine rotor, having a segment of five blades 11-11 mounted thereon. The blades 11-11 are tied together by means of two lashing wires 12 and 13 inserted in suitable holes 14 and 16 provided in the blades. Intermediate the blades 11-11 the lashing wires 12 and 13 are drawn together, as at 17-17 and joined to each other, preferably by fusion of metal, such as welding, soldering or brazing.

In applying the form of lashing indicated in Fig. 1, the lashing wires are threaded through the holes 14 and 16 in the blades 11 upon assembly of the blades in the blade holding element. The lashing wires may then be drawn together, as at 17, and secured in the manner set forth. Preferably the lashing wires 12 and 13 are secured to the blades 11-11, thus adding additional stiffness to the structure. The manner of securing the wires 12 and 13 to the blades may be any known to those skilled in the art.

In Figs. 2 and 3 I show a modified form of my invention wherein the blades 11-11 are provided with holes 14 and 16, as previously shown. However, in this modification I provide individual lashing members 18-18 in the form of split rings or links which are applied to the blades in the process of manufacture and closed as at 19.

The outer ends of the links may be reduced in thickness on alternate sides, as shown at 21—21 in Fig. 3, so that upon assembly the outer ends overlap each other intermediate 5 the blades. Upon assembly, the overlapping portions of the rings are joined together by fusion of metal, as at 22, thus providing a sturdy, unitary structure.

In Fig. 4 I show a further modification in 10 which the reaction blades 11—11 are provided with holes 26—26 which are normal to the axes of least resistance of the blades, said axes being indicated at *a—a*. Inserted in the holes 26—26 are lashing members 27 15 similar to the members 18 illustrated in Fig. 2 except that the angular relation of the blades to each other permits the ends to overlap as shown, facilitating assembly and removing the necessity of flattening the ends 20 as shown in Fig. 2. My improved lashing, applied in this manner gives the greatest resistance to flexure of the blading.

Referring now to Fig. 5, I show a method of lashing a segment of blades, particularly applicable to the modification of my invention shown in Fig. 4 and also particularly applicable to short reaction blading where there is limited room between the blades for the insertion of soldering or welding tools. In accordance with this method, a segment of blades 11—11 is mounted in a suitable base 28 made of insulating material and conforming in contour to the blade holding element in which the blades are to be 25 finally inserted. Interposed between each of the blades 11—11 at the roots thereof is a spacing member 29 also made of insulating material. After mounting in the manner shown with the lashing members 27—27 30 overlapping between blades, and in contact, electrodes 31 and 32 of an electric welding apparatus are connected to the lashing members 27 at opposite ends of the segment and suitable pressure applied to each joint, if 35 necessary, after a welding temperature is reached. The several lashing members are thus welded together intermediate the blades without subjecting the blades to the welding heat. After welding, the blades and spacing members are removed from the base 28 40 and the blades with permanent spacing members are permanently mounted in a blade holding element.

It should be noted that in each form of 50 my invention no lashing member goes directly across from blade to blade, but that a more or less indirect or serpentine route is followed. Thus, upon heating and cooling, the lashing may deflect slightly and remain 55 tightly attached to the respective blades, at the same time having sufficient rigidity to effectually prevent vibration.

From the foregoing it will be apparent that I have devised an improved lashing

means for turbine blades effective for resisting, to a maximum degree, flexure of the blading in service, simple of construction and easy of application.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. Lashing means for turbine blades comprising cooperating lashing members secured at two points to a blade and joined together intermediate adjacent blades in a row.

2. Lashing means for a row of turbine blades having at least two series of aligned holes, comprising lashing members inserted in the holes and joined together intermediate adjacent blades.

3. In a turbine, a row of blades having an inner and an outer series of aligned holes, lashing members inserted in the holes and joined together intermediate the blades by fusion of metal.

4. In a turbine, a row of blades having an inner and an outer series of aligned holes, lashing members inserted in the holes, secured to the blades and joined together intermediate the blades by fusion of metal.

5. In a turbine, a row of blades, individual lashing members secured to each of the blades normal to the axis of least resistance thereof and joined together intermediate adjacent blades in a row.

6. In a turbine, a row of blades having an inner and an outer series of aligned holes, individual lashing members comprising links having a portion extending through each of the holes and secured to each of the blades, and means joining the lashing members together intermediate adjacent blades.

7. In a turbine, a row of blades having an inner and an outer series of aligned holes, individual lashing members comprising links having a portion extending through each of the holes normal to the axis of least resistance of the blades and secured to the blades, and means securing the lashing members together intermediate adjacent blades.

8. In a turbine, a row of blades, lashing members therefor each secured to at least two places on a blade, extending indirectly to an adjacent blade and joined to another lashing member intermediate the blades.

In testimony whereof, I have hereunto subscribed my name this twenty-seventh day of August, 1925.

JAMES L. RAY,
